MINIATURE ELECTRIC FREEZER
Francis A. Hill 2nd, 23 Campo Parkway,
Westport, Conn.
Filed Jan. 8, 1958, Ser. No. 707,764
9 Claims. (Cl. 62—506)

My invention relates to a miniature portable electric freezer. It will freeze from one to three ice cubes in five to fifteen minutes. It weighs less than 6 pounds and can be carried in a suitcase while travelling. It can be used on small yachts and as a toy for children.

One of the objects of my invention is to provide for rapid cooling of the compressed hot refrigerating gases with the least amount of radiating surface.

A second object of my invention is to provide means for cooling the electric motor.

A third object of my invention is to provide means to cool the electric motor with part of the compressed and condensed refrigerant.

A fourth object of my invention is to provide means for two stages of compression.

A fifth object of my invention is to provide a compressor which is essentially two cycle in operation.

A sixth object of my invention is to provide a miniature electric freezer with the parts so arranged that the condenser coils, the compressor and the electric motor may be immersed in water and cooled.

In the figures:

FIG. 1 is a vertical sectional elevation of my miniature freezer on line 1—1, FIG. 2, using an opposed piston compressor.

FIG. 2 shows a sectional view of my freezer on line 2—2 in FIG. 1.

FIG. 3 shows a pair of "Rotoid" gears which can be used for compressing a refrigerant gas.

FIG. 4 is a bottom view of the freezer using a two stage piston compressor with a cooling coil between the stages on line 4—4 in FIG. 5.

FIG. 5 is a right hand view of FIG. 4 with the outer shell in section.

FIG. 6 is a vertical section showing the gears in FIG. 3 at the bottom end of my miniature freezer.

FIG. 7 is an inside view of the bottom port plate in FIG. 6.

FIG. 8 shows a simpler construction than in FIG. 1, a two-way valve, and an internal gas cooling circuit for the motor.

FIG. 9 shows an outer shell with inner ribs arranged so as to permit expansion of internal members without undue stress.

FIG. 10 shows a four section ice tray for four pieces of ice.

When travelling in Europe few hotels and motels have the ready quantities of ice to which we are accustomed in America. A freezer which is light to carry and which can make a few cubes of ice quickly will be very useful. For this reason I show it set in a wash basin A with running water from a faucet B to cool the condenser coil 23. The water can overflow at C and down the drain pipe at D. In FIG. 1 the cylindrical casing 1 contains the ice tray 2 and cover 3, evaporator 4, insulated chamber 5, motor 7 inside a hermetically sealed inner casing 32 with a drive shaft 8 projecting into a compressor housing 9 with cover 9A. This housing 9 has a cylindrical flange 9B enclosing and sealing the casing 1 and is cooled by water when in the basin of water A. The other end of the casing 1 is sealed by the member 5A. On the shaft 8 is rigidly mounted an eccentric 10 carrying the pin 11 which engages the link 12 which has another pin 13 which engages the opposed piston member 14. Rotation of the shaft 8 causes piston member 14 to reciprocate

2
in its cylinders 27A and 28A in the housing 9. The left end of piston 14 is shown at the end of its compression stroke and the right end at the end of the suction stroke with the intake port uncovered completely. The pocket 14C acts as an oil reservoir. It holds enough oil to lubricate the piston member 14 while reciprocating.

At the outer end of each compressor cylinder 28A and 27A are valves 15 and 16 held in position by springs 17 and 18. Cylinder caps 19 and 20 close the ends of the cylinders. During compression the valves 15 and 16 lift to permit compressed refrigerant to escape into passageways 21 and 22. Passageways 21 and 22 connect with an annular groove 23 in the housing 9. Groove 23 acts as a receiver and the gas in it is cooled by the shell 1 and the water outside of it in the basin A in FIG. 1. Gas in the groove 23 and whatever condensed refrigerant there may be flows up through coil 24 where it is cooled some more and into the evaporator 4 where it is restricted by a capillary tube 25. From 4 the gas returns to the compressor by the conduit 26. 26 connects into another annular groove 26A in housing 9. Passageways 26B and 26C return the gas to the intake ports 27 and 28. Opening 26D allows oil to spill out and down into the reservoir 14C.

25 In my miniature freezer the piston will have a diameter and stroke of about $\frac{3}{16}$ of an inch. Cylinder clearances can be reduced to zero by having the valves 15 and 16 close to the ends of the cylinders and having the outer ends of the piston practically flush with the outer ends of the cylinders at the ends of the compression strokes.

The intake ports 27 and 28 are uncovered when the pistons approach the low pressure ends of the cylinders and are covered again a short bit after the start of the compression strokes. Since there are two compression 35 strokes per revolution power from the motor is used throughout each rotation of 360° . The power required is that needed for compression in one cylinder plus the small amount of power to create the vacuum in the other before the intakes are uncovered. In this construction 40 the same size motor can be used for two pistons and cylinders as for one piston and cylinder. This is especially true when the motor has the usual reserve power of a well designed unit.

The freezer casing 1 has openings 29 for the circulation of cooling water around the coils 24. Openings 29 permit water circulation around the compressor housing 9 (FIGS. 1 and 5).

The motor 7 is inside a hermetically sealed casing 32 which is cooled on its outside by water between it and the condenser coils 24. By having the motor in contact 50 thermally with the casing 32 it is cooled also. This motor is of a sub-fractional horse power between $\frac{1}{50}$ and $\frac{1}{20}$ depending upon the sizes of the pistons. It can be connected to a source of electricity by the cord E passing from the motor thru a gas tight joint in the casing wall 32 and out thru 1. In order to avoid bursting mechanical stresses on the casing 32 ribs 33 (FIG. 9) set at an angle to the radius R which can flex a few thousandths of an inch as indicated by the arrows 34 to relieve the outward 55 expansion of the motor 7 in the direction of the arrow 35.

60 When additional condensing surface is needed another spiral coil 24A (shown in dotted lines) can connect the compressed discharged refrigerant in the annular groove 23 (by spiralling upward between the coils 24) with the junction 24B. The compressed condensed refrigerant from both coils 24 and 24A then enters the evaporator 4.

FIG. 8 is partly in section and partly schematic. It shows my miniature freezer without an outer shell. Condenser pipes 36 and 37 (similar to 24 and 24A in FIG. 1) deliver refrigerant to a two way valve 38 near the top of the freezer. When the valve piston 39 is in the position shown in solid lines, condensed refrigerant from 37 enters

the valve chamber to the left of the piston and exits at 40 into the capillary tube 25A from which it expands in the evaporator 51. Condensed refrigerant from 36 enters the valve chamber to the right of the piston and leaves by the tube 62. It then flows downward into chamber 63, thru holes 64 and 65, thru the motor spaces, out of the motor spaces and thru holes 66 and into groove 26A (indicated by arrow 66A) and into the intake ports 27 and 28 as shown in FIG. 1.

When the valve piston is pushed to the right as shown in dotted lines, the condensed refrigerant from 36 joins that from 37 and enters the evaporator as described above. Conduit 61 returns the gas from the evaporator to the annular groove 26A.

In FIG. 4 I show a two stage compressor. The right hand piston 14A compresses gas for the first stage from whence it goes out of the discharge port at 22 into the cooling coil 21A and then to the intake 29 for the second stage of compression by the piston 14B and delivered to the condenser coil 24 in FIG. 1. The coil 22A is of course cooled by the water in the basin. This basin need not be a wash basin. It can be a dish pan or a pail of water. When the water gets too warm it can be dumped out and fresh water put in. When the freezer is made of corrosion resistant enamel salt water can be used as the cooling fluid when in a boat on the sea.

FIG. 3 shows a pair of Rotoid gears (Pat. No. 2,666,336). FIG. 6 is a vertical section thru a Rotoid compressor showing the inner gear 50 having 5 teeth and the outer gear 51 having 7 teeth. 50 is journaled on the fixed shaft 53. 51 is mounted on the back plate 52 which is keyed to and driven by a motor shaft 54 journaled in the housing 59 at 55. This housing 59 has a flange 59B enclosing and sealing the compressor end of the casing 1. The intake port is indicated at 58 and the discharge port at 57 in FIGS. 6 and 7. The return tube 26 connects with the intake port 58. The discharge port 57 connects with the condenser coil 24. These gears are inherently two cycle in action.

This miniature freezer is not much larger than the drawing in FIGURE 8. The top of the plastic bucket indicates the preferred level of the water when the unit is partially immersed.

I do not limit my invention to the particular construction shown. The motor may be horizontal instead of vertical. The condenser coil or coils may be inside or outside of the casing 1. Other types of compressors may be used. The essence of my invention consists of a miniature freezer which has to be set in water in order to cool the condensing gases, to cool the electric motor and to cool the compressor. To be sufficiently light and portable my miniature freezer has to be designed without adequate cooling means. The user must supply the bath of water in which to immerse the little freezer so that the refrigeration cycle will be efficient.

What I claim is:

1. In a miniature portable freezing unit, a casing, an ice chamber at one end of said casing, a loose fitting cover for said ice chamber, an expansion chamber containing a capillary tube and adjacent to said ice chamber and hermetically sealing said casing, a motor driving and attached to a compressor inside said casing, a housing for said compressor hermetically sealing the opposite end of said casing, the outer surface of said motor being in contact with the inner surface of said casing, intake and discharge ports for said compressor, conduits between said ports and said expansion chamber and said capillary tube, and having the surface of said motor and conduits containing hot refrigerant cooled when said miniature portable freezing unit is in contact with and partially im-

mersed in a separate and unattached body of cooling water.

2. The combination according to claim 1, and having a container separate and detached from said freezing unit for holding said body of water.

3. The combination according to claim 1, and having a pocket for holding a lubricant in said compressor in said housing.

4. The combination according to claim 1, said compressor comprising two opposed pistons in line with each other and rigidly connected together, a first member engaging said pistons, a second member mounted eccentrically to the drive shaft of said motor, a link engaging said first and second members so as to cause said pistons to reciprocate when said shaft rotates and carries said second member around during each revolution, counter balancing means on said shaft, discharge valves at the ends of each cylinder of said compressor pushed off their seats by the compressed gas during discharge and returned to their seats shortly after the start of the intake stroke by springs, intake ports near the other ends of said cylinders and uncovered by said pistons near the end of the intake stroke and closed by said pistons shortly after the start of the compression stroke.

5. The combination according to claim 1, and having compressed refrigerant flow through two conduits between the compressor and the expansion chamber.

6. The combination according to claim 1, having two grooves around the housing of said compressor, one groove connected to the intake port or ports and the other connected to the discharge port or ports, each of said grooves being closed by a casing inner surface so that the refrigerant in said grooves is cooled by said casing when said miniature freezer is immersed in water.

7. The combination according to claim 1, two conduits from said compressor containing compressed discharged and condensed refrigerant connected to a two way valve, said valve having two settings, one to send said refrigerant in both of said conduits into said expansion chamber and the other to send the refrigerant from one conduit into said expansion chamber and the refrigerant from the other of said conduits into the inside of said casing containing said motor, and having passageways connecting to the intake of said compressor.

8. The combination according to claim 1 having a second casing outside of and surrounding said casing containing said motor and compressor, and openings in said second casing to permit water to come in contact with the outside of said casing containing said motor and compressor.

9. The combination according to claim 1, said compressor consisting of two opposed pistons connected together, one piston being a large piston for a first stage of compression and the other a smaller piston for a second stage of compression, means to drive said pistons, a cooling conduit between the cylinders of said pistons, said conduit being cooled by water outside of said casing when said freezer is immersed and when refrigerant flows from the larger to the smaller cylinder.
